UNITED STATES PATENT OFFICE.

ELI J. MILLER, OF YORK, PENNSYLVANIA.

DISH-WASHING MACHINE.

1,032,018.

Specification of Letters Patent. Patented July 9, 1912.

Application filed February 21, 1912. Serial No. 679,148.

To all whom it may concern:

Be it known that I, ELI J. MILLER, a citizen of the United States, residing at York, in the county of York and State of Pennsylvania, have invented certain new and useful Improvements in Dish-Washing Machines, of which the following is a specification.

My invention relates to improvements in dish washing machines.

The object of my invention is to provide a dish washer which, while simple enough to be readily understood and operated by unskilled persons, will subject the dishes to a thorough washing action of the water and this without the necessity of employing a large amount of water.

The invention will be understood from the description hereinafter of the preferred embodiment thereof.

In the drawings,—Figure 1 is a longitudinal vertical section of an apparatus embodying my invention; Fig. 2 a plan view of the apparatus; Fig. 3 an end elevation 25 of the same; Fig. 4 a transverse vertical section through the center of the apparatus. Fig. 5 a longitudinal vertical section through the spring device.

Referring to the drawings, A is a rectangular tank, in the present case having a length greater than its width. The back a' and ends a' of this tank are most advantageously formed of wood, while the bottom and front are advantageously made of one piece of sheet metal, the upper front edge being rolled over as indicated at a^2 to form a suitable rim. The sheet metal forming the bottom is reflexed upward to form an inverted, truncated V-shaped central portion a^3 extending the full length of the tank, whereby the interior of the tank is divided into two separate and independent water-holding compartments narrower at their bottoms than at their tops, the central portion extending to any desired height up the interior of the tank so that the water-holding compartments will have a depth sufficient to hold the water required to wash the ordinary dishes.

50 The tank A is arranged to receive a dish-holding basket B, which is shaped to conform to the interior of the tank A, the bottom of said basket being bent upward as indicated at b so as to conform to the upward projecting portion a^3 of the tank. This upward projecting portion b of the

basket bottom extends the full length of the basket, and thus divides said basket into two portions or dish-receiving compartments, and the straight walls of the inverted V-shaped central portion serve to support the dishes which may be placed on edge in the basket and lie against the said inclined sides so as to permit a ready stacking of the dishes in the basket. The basket B is made of any suitable perforated material but particularly wire cloth, its upper edge being reinforced with a sheet metal rim b^2 as shown. At each end the basket rim is provided with handles as indicated at b^3 and also, inside of the handles, with swinging hooks by which the basket is detachably connected to an operating mechanism as hereinafter described. This operating mechanism in the present example comprises a frame attached to the tank in such a manner as to be especially suitable as a handle or bail by which the tank may be carried. This frame or bail is formed of round iron rod and has two uprights, c , pivoted to the ends of the tank, one of said pivotal points being indicated at c' , Fig. 1. The uprights, c , are connected by a cross piece, c^2 , which is bent upward at two points as indicated at c^3 , for a purpose hereinafter explained. 85 In order to hold the bail or frame in its erect position, the ends of the uprights are provided with suitable holding devices such for example, as sliding bolts, d , arranged to engage socket pieces, d' , secured to the ends of the tank below the uprights. Each upright is provided with a slide, E, each of which carries an outward extending bearing, e , through which extends, axially, a threaded clamping bolt, f , having a handle, 90 F, which is made of sufficient size to be grasped by the entire hand for a purpose hereinafter explained. Each slide, also is provided with an inward extending arm which at its lower surface carries a transversely arranged downward facing channel member or engaging device, e' , arranged to engage the upper edge of the basket at the ends thereof. Each of these channel members is provided at the rear of the respective slide members with a notch as indicated at e^2 .

The inner face of each basket end is provided near its top, with two swinging latch devices, g , g' , arranged to be swung upward 110 to engage the upper surface of the respective channel devices, the rear latch devices

being arranged to engage the respective notches, e^2 , at the rear of the slide devices.

A suitable counterbalancing mechanism is connected to each slide device, this mechanism in the present example consisting of an adjustable spring mechanism connected between the respective slide device and the corresponding upward bent portion, c^3 , of the cross piece. In the present embodiment 10 of the invention, the spring mechanism is of the duplex type, that is to say, each comprises a pair of helical springs, h, h' , of different diameters, one located inside the other, the outer spring having its upper end 15 secured to an upper cap, h^2 , which is connected to a chain of several links, h^3 , which are arranged to engage a hook, c^4 , secured to the upright. The lower end of the outer spring is connected to a lower cap, h^4 , upon 20 which the lower end of the inner spring rests and to which it is secured. Upon the upper end of the inner spring rests a cap, h^5 , to the center of which is secured a rod, h^6 , extending downward through the center 25 of the inner spring and terminating in a hook, h^7 , arranged to engage an eye, e^8 , carried by the inward extending arm of the slide device. The spring mechanism is advantageously provided with indicating mechanism 30 for a purpose hereinafter explained, this consisting in the present instance of a slotted front plate, h^8 , provided with any suitable graduations, and an index, h^9 , attached to the rod and movable in the slot. 35 The front plate is attached to an inclosing casing, h^{10} , which is connected to the upper cap, h^2 , to which the outer spring is attached.

For the purpose of conveniently operating 40 the apparatus, a lever mechanism is provided, this consisting in the present example of a pair of side levers, K , each fulcrumed at its rear end on a link, k , pivoted at its lower end at any suitable place, as for 45 example, to the outside face of the respective end pieces of the tank. Each lever is provided on its under side with a jaw, one of which is indicated at k' , which jaw is arranged to engage the outward extending 50 bearing, e , of its respective slide device. The front ends of the levers are connected by a suitable handle bar, K' .

The tank is provided with two spigots, L , one for each compartment.

5 The operation of my device is as follows: Water is supplied to the tank to fill its two compartments to the desired height. The dishes to be washed are placed in the basket in the respective compartments in a suitable 10 inclined position, edge downward and with the dirty sides facing downward. If the indicating devices on the spring mechanism indicate that one spring is supporting less than the other, the tension of said spring 15 may be increased by shortening the support-

ing portion of the chain which holds said spring at the top, until the indicators of both springs are approximately at the corresponding graduations. The basket is now reciprocated up and down, either by oscillating the handle bar, K' , or if desired, by direct application of the hands of the operator to the handles, F . This vertical reciprocation of the basket causes a strong agitation 75 of the water against the dishes and thereby 80 cleans the dishes in an effective manner. At the termination of this operation, the basket may be allowed to rise under the influence 85 of the springs, and by turning the handles, F , said basket may be locked at any desired 90 height to allow the dishes to drain. The lever mechanism can be swung upward and backward out of the way. When the dishes are sufficiently drained, the basket with the 95 dishes may be removed from the machine by first throwing the lever mechanism upward and backward out of the way, then swinging inward the rear latch devices and finally 100 sliding the basket forward, the front latch devices, g , serving to support the basket during this sliding operation. To replace the basket, it is not necessary to slide it back into place, which is not a convenient method, but the front latch devices will swing inward as soon as released from the 105 engaging device, and in replacing the basket it is inserted into place beneath the engaging device and then first the front latch devices and subsequently the rear latch devices 110 are swung upward to hold the basket to the 115 engaging devices.

It will be seen that the tank may be lifted and carried by the cross piece, c^2 , which with its uprights serves as a bail for the tank. Furthermore, the said bail may be 120 swung back out of the way at any time by releasing the bolts, d , at the bottoms of the uprights. This is particularly advantageous when it is desired to clean the tank or to use the latter without the basket for washing 125 such articles as cannot be satisfactorily washed in the dish-basket by mere reciprocation, for example, tureens, tea pots and the like hollow-ware articles. In this way the apparatus is particularly suitable for domestic purposes, since the tank itself is always 130 available as a dish-pan, and owing to its two separate compartments a sufficient depth of water for ordinary dishes is provided without the necessity of using a large amount of water, which when hot water is used, is a considerable economy. Furthermore, it is to be noted that the flat top of the central upward extension of the tank serves as a rest or table upon which the dishes to be washed 135 in the tank, such as tureens and the like, may be rested while being cleaned by hand, and since this flat top is usually approximately but slightly above the level of the water in the two compartments the dish to 140

be washed is brought close to the water and yet need not be submerged in the same when washing it with a cloth, nor held wholly by the hand. This flat top also is very convenient in scouring cutlery at the close of the dish washing operation, which is customarily done upon a table top at one side of the dish pan. Because of the fact that this flat top of the central partition is below the level of the top edge of the tank there is less likelihood of splashing water about the premises when doing such work on the said flat top.

Having thus fully described my invention, what I claim is:

1. In a dish - washing apparatus, a tank having a centrally arranged, upward extending, truncated, inverted V-shaped partition separating the tank into two independent compartments, the flat top of said partition lying below the top of the tank.

2. In a dish-washing apparatus, the combination, with a tank having a centrally arranged partition separating the tank into two independent compartments, said partition having its sides arranged as plane surfaces sloping upward toward each other, the upper surface of said partition lying below the plane of the upper edge of the tank, of a dish basket having its bottom bent upward to form a centrally arranged upward - extending partition conforming generally to the shape of the tank partition, the sides of said basket extending above the top of its partition, and means for giving said basket a reciprocatory motion in said tank.

3. In a dish-washing apparatus, the combination, with a tank, and a basket arranged to be received within said tank, of a bail device pivotally connected to the ends of the tank and arranged to be swung back out of the way, means for locking said bail device in an upright position, slides carried by said bail device and movable thereon, a counterbalancing mechanism connected to the slides and to the bail, means for detachably connecting the basket to the slides, and means for reciprocating said slides.

4. In a dish-washing apparatus, the combination, with a tank, a basket arranged to be received therein, a pair of uprights, one connected to each end of the tank, and a cross piece connected to both uprights, of a pair of springs, an indicating device for indicating the tension on each spring, means for connecting each spring to one end of the basket, and means for adjustably and inde-

pendently connecting each spring to the cross piece, whereby the tension on each spring may be varied independently of that on the other.

5. In a dish-washing apparatus, the combination, with a tank, a basket arranged to be received within said tank, and uprights connected one to each end of said tank, of a slide surrounding each upright and movable vertically thereon, each slide having a hollow outward - extending bearing, provided with an internal screw - thread, a screw threaded into each bearing and arranged to clamp the respective upright, a handle carried by each screw, means for detachably connecting the basket to both slides, means for counterbalancing the basket, and an operating device comprising levers provided with means for detachably engaging the respective bearings of the slides.

6. In a dish washing apparatus, the combination, with a tank, and a basket arranged to be received within said tank, of a pair of uprights carried by the ends of the tank, a cross-piece connecting the said uprights, a slide movable on each upright, each slide carrying a transversely arranged channel member arranged to receive the upper edge of the corresponding end of the basket, and means for locking the basket rigidly to the said channel members.

7. In a dish washing apparatus, the combination, with a tank, and a basket arranged to be received within said tank, of a pair of uprights carried by the ends of the tank, a cross-piece connecting the said uprights, a slide movable on each upright, each slide carrying a transversely arranged channel member arranged to receive the upper edge of the corresponding end of the basket, each slide also having an outward extending bearing, means for locking the basket to the said channel members, levers fulcrumed behind the uprights and provided with downward opening jaws arranged to engage the outward extending bearings of the slides, a handle bar connecting said levers, and means carried by each slide for locking the slides at any desired height on the uprights.

In witness whereof I have hereunto affixed my hand this 20th day of February, 1912.

ELI J. MILLER.
